UNITED STATES PATENT OFFICE.

ALONZO L. BLANCHARD, OF ALBANY, NEW YORK.

DESIGN FOR A STOVE.

Specification forming part of Design No. 66, dated July 25, 1846.

To all whom it may concern:

Be it known that I, ALONZO L. BLANCHARD, of Albany, in the county of Albany and State of New York, have invented or produced a new ornamental Design for a Statue-Stove; and I do hereby declare that the following is a full, clear, and exact description of the same, reference being had to the accompanying drawings, making part of this specification.

Figure 1 represents a perspective view of a stove after my design, surmounted by the statue of a female in modern drapery.

Fig. 2 represents the front lower plate, consisting of a panel containing a female figure holding a wreath in the left hand and extending the right arm toward the sea. Two vessels are seen upon the water, which is bounded in the background by distant hills. The figure reclines upon rocks and has foliage behind it. The panel is bordered with heavy scroll-work and foliage. The rear is the same, except that the filling of the panel is omitted.

Fig. 3 represents the plate forming the two ends. A bouquet of flowers and foliage, with a rose in the center, fills the middle, the border being composed of foliage and scrolls, with a single scallop-shell in the center at the bottom.

Fig. 4 represents the plate forming the front

and rear of the upper portion, and presents a figure composed of foliage and scrolls, with a winged boy, naked, seated thereon and playing upon a flute.

Fig. 5 represents the plate forming the two ends of the upper portion, consisting of scrolls, foliage, and flowers.

To save labor in drawing, portions of Figs. 2, 3, and 4 have been left blank, the figures being similar to and symmetrical with the parts represented.

Fig. 6 represents the surmounting statue upon a larger scale. The figure is that of a young female in modern attire, the left hand engaged with the drapery at the side and the right laid upon the bosom. The dress has a double ornamented border. A necklace encircles the neck and bracelets the arms.

What I claim as my invention, and desire to secure by Letters Patent, is—

The combination and arrangement of ornamental figures herein shown and described, forming an ornamental design for a statue-stove.

ALONZO L. BLANCHARD.
